UNITED STATES PATENT OFFICE.

ALFRED A. GLIDDEN AND THOMAS M. KNOWLAND, OF WATERTOWN, AND WILLIAM T. RICH, JR., OF NEWTON, MASSACHUSETTS, ASSIGNEES TO HOOD RUBBER COMPANY, OF WATERTOWN, MASSACHUSETTS, A CORPORATION OF MASSACHUSETTS.

VALVE-STEM ADAPTER FOR INNER-TUBE MOLDS.

Application filed September 30, 1927. Serial No. 223,083.

This invention relates to a valve stem adapter for inner tube molds.

The object of the invention is to provide a device which will encircle and interlock with the valve stem of an inner tube, and also be so associated with the mold for said inner tube at the point where the valve stem passes outwardly therethrough that the material of which the inner tube is constructed will not 10 flow around the valve stem during the vulcanizing operation, thereby clogging the threads of the valve stem and making it necessary to remove the material from the threads.

Another very important object of the invention, which is attained by our improved adapter, is that the portion of the tube immediately surrounding the valve stem and known as the valve base is prevented from 20 leaking out around the valve stem, which would weaken the portion of the tube immediately adjacent to the valve stem. The tube, by the use of our adapter is thus left of its original form and thickness and strength.

The invention consists in a mold and valve stem adapter therefor as set forth in the following specification and particularly as 25 pointed out in the claims thereof.

Referring to the drawings:

Figure 1 represents a plan view of a mold for an inner tube and valve stem adapter therefor embodying our invention.

Fig. 2 is an enlarged transverse section through the mold as taken on the line 2—2 of Fig. 1, an inner tube and valve stem adapter being illustrated in position within the mold.

Fig. 3 is a detail section taken on the line 3—3 of Fig. 2.

Fig. 4 is a side elevation of the adapter.

Like numerals refer to like parts throughout the several views of the drawings.

In the drawings, 5 is an annular tubular mold for an inner tube 6, said mold consisting of two semi-tubular sections 7 and 8 45 hinged together at 9. The section 7 has an outer flange 10 extending therearound and an inner flange 11 also extending therearound. The section 8 has an outer flange 12 and an inner flange 13 extending therearound.

The inner tube 6 is provided with an air valve stem 14 of well-known construction, and when the inner tube is in position within the mold the valve stem 14 projects into and

through a sleeve 15 which constitutes the adapter of this invention.

The sleeve 15, in addition to projecting through an opening provided therefor in the mold section 8, is held securely in position upon the flange 13 of said mold section by a cap 16, the latter being fastened to the said flange by screws 17. The sleeve 15 has a tapered head portion 18 formed at one end thereof, said head portion fitting a correspondingly tapered recess 19 provided in the mold section 8. The sleeve 15 is rotatable within the mold section 8 and may also slide longitudinally thereof within said mold section, said longitudinal movement being limited in one direction by the head portion 18. The sleeve 15 has a bore 20 extending partly therethrough, said bore terminating in an internally screw-threaded portion 21 which has screw-threaded engagement with the valve stem 14, so that by rotating the sleeve 15, the valve stem can be drawn into the 75 sleeve 15, thus bringing the inner tube 6 into contact with the inner end of the sleeve and clamping the inner tube between a flange 22 provided upon the valve stem and the inner end of the sleeve. A portion of the exterior 80 surface of the sleeve 15 is knurled at 23 to facilitate the manual rotation of said sleeve upon the valve stem 14 and within the mold section 8.

In utilizing the device of this invention the sleeve 15, constituting the adapter, is attached to the valve stem 14 of the inner tube 6, the inner tube being tightly clamped between the flange 22 of the valve stem and the extremity of the sleeve. The inner tube in a partially inflated condition is placed within the mold section 8 with the valve stem and sleeve projecting through the opening provided therefor in the mold section. The mold section 7 is then closed upon the section 8 and clamped thereto and the inner tube then inflated, the pressure of air within the inner tube holding the latter in the position illustrated in Fig. 2 and with the head 18 of the sleeve 15 seated within the recess 19 of the mold section 8.

The operation of vulcanizing the inner tube may then be performed without danger of the material of which the inner tube is constructed, and especially the valve base, flowing around the valve stem 14 and clogging 105 the threads thereof, thereby making it neces-

sary to remove said material from the threads after the inner tube is removed from the mold, and also thereby weakening that portion of the tube known as the valve base immediately adjacent to the valve stem as hereinbefore set forth.

We claim:

1. In combination a mold, and a sleeve rotatably mounted therein, said sleeve being constructed and arranged to encircle and to have screw-threaded engagement with the valve stem of an inner tube located within said mold to clamp said inner tube to the sleeve.
- 10 2. In combination a mold, and a sleeve rotatably mounted therein, said sleeve being constructed and arranged to have screw-threaded engagement with the valve stem of an inner tube located within said mold to

clamp said inner tube to the sleeve, the sleeve also being slidable longitudinally thereof within the mold.

3. In combination a mold, and a sleeve rotatably mounted therein, said sleeve being constructed and arranged to have screw-threaded engagement with the valve stem of an inner tube located within said mold to clamp said inner tube to the sleeve, the sleeve also being slidable longitudinally thereof within the mold and being provided with a head portion engaging the mold and limiting said longitudinal movement in one direction.

In testimony whereof we have hereunto set our hands.

ALFRED A. GLIDDEN.
THOMAS M. KNOWLAND.
